DESIGN FOR A MOTOR POWER VEHICLE CAB

Emery Rossner, Brooklyn, N. Y., assignor to Milford Crane & Machine Co., Milford, Conn., a corporation of Connecticut

Application October 19, 1946, Serial No. 134,084

Term of patent 14 years

(Cl. D14—3)

To all whom it may concern:

Be it known that I, Emery Rossner, a citizen of the United States of America, residing at Brooklyn, Kings County, and State of New York, have invented a new, original, and ornamental Design for a Motor Power Vehicle Cab, of which the following is a specification, reference being had to the accompanying drawing, forming part thereof.

Fig. 1 is a perspective view, showing the rear end of the motor power vehicle cab.

Fig. 2 is a perspective view showing the front end of the cab, certain portions being broken away to show the seat and the compartment walls.

The dotted line showing in the drawing is for illustrative purposes only.

I claim:

The ornamental design for a motor power vehicle cab, substantially as shown and described.

EMERY ROSSNER.
